UNITED STATES PATENT OFFICE.

DONALD J. CAMPBELL, OF MUSKEGON, MICHIGAN.

ALUMINUM INLAID PISTON.

Application filed June 20, 1927. Serial No. 199,928.

This invention relates to a composite piston or one in which two metals are used in producing the piston, one usually being cast iron and the other aluminum. It is an object and purpose of the present invention to produce a piston wherein aluminum is used to form the major portion of the head of the piston, being cast in such a manner in conjunction with the cast iron part of the piston that it may be said to be inlaid at the top and at the upper portions of the sides of the piston and securely interlocked with the cast iron part and held very firmly against any possibility of disconnection or loosening. At the same time the piston ring grooves formed in the piston are partly through the aluminum and partly through the cast iron, whereby the ring grooves are not wholly in aluminum, but being also partly in the cast iron are strengthened and reinforced against possibility of battering and widening, which occurs many times in either aluminum or composite pistons having aluminum heads in which the ring grooves are made.

An understanding of the invention may be had from the following description in connection with the accompanying drawings, in which

Fig. 1 is a plan view of the piston with a part thereof broken away and shown in section.

Fig. 2 is a vertical section through the piston substantially on the plane of 2-2 of Fig. 1.

Fig. 3 is a fragmentary side elevation of the upper end of said piston, and

Fig. 4 is a fragmentary vertical section on the line 4-4 of Fig. 1.

Like reference characters refer to like parts in the different figures of the drawings.

In the construction of the piston a skirt 1 of cast iron is made, from which integral inwardly extending bosses 2 project to serve as wrist pin bearings. Above said bosses the piston is continued and formed into a closed top 3 which, at its upper side, is provided with a plurality of radial upwardly extending ribs 4 extending from points near the center of said top outwardly and increasing in width as the same extend outwardly, said ribs at

their outer ends joining with vertical ribs 5 at the curved outer side of the piston and which lie in the same planes as the outer sides of the skirt 1. This makes grooves 6 at the outer vertical sides of the upper end of the cast metal part of the piston between the ribs 5 which at their upper ends join with the spaces between the top ribs 4. The ribs 4 are dovetailed in form, that is, are undercut at their sides and inner ends and, similarly, the ribs 5 are undercut as shown in Fig. 1 so as to be of dovetail form. In addition, at the lower ends of the ribs 5 a groove 7 is made so that below the lower ends of said ribs 5 a continuous groove is made entirely around the cast metal part of the piston at its upper side joining with the vertical grooves 6 between the ribs 5, this groove, where it passes underneath the lower ends of the ribs 5 is also in dovetail form, being wider at its bottom than at its outer side.

Over the upper end of the cast metal part of the piston described, the aluminum portion of the piston is cast so as to fill the spaces between the ribs 4 and 5 and fill the groove 7. This provides a top 8 of aluminum, the upper side of which lies flush with the upper side of the ribs 4. Integral with this top are downwardly extending sides 9 between the ribs 5 which integrally join a ring 10 at their lower ends which extends through the groove 7 below the lower ends of the ribs 5 above a shoulder 7^a formed around the cast metal part of the piston a short distance above the wrist pin bearing bosses 2, said shoulder forming the lower side of the groove 7 previously described. In the aluminum sides 9 of the aluminum head thus made and in the ribs 5 of the cast iron in the head of the piston ring, piston ring grooves 11 are made, it being evident that the ring grooves are partly in the aluminum and partly in the cast iron.

The composite piston thus made of cast iron and aluminum is one wherein the aluminum is positively and securely interlocked with the cast iron part of the piston and cannot become disconnected therefrom or even loosened with respect thereto. The melted aluminum flows into all of the recesses in the cast iron part of the piston filling the same and con-

necting with the dovetailed construction of the ribs 4 and 5 and the groove 7 a very secure and positive connection of the aluminum part to the cast iron part of the piston is made.

5 Aluminum being a very good conductor of heat, better than cast iron, carries the heat absorbed by the piston from the explosions to the rings and to the walls of the cylinder.

The piston is equipped with wrist pin bearing

10 bosses of cast iron, which is very desirable and the ring grooves are partly in the cast iron which is better than to have such grooves wholly in the aluminum, because of the softer character of aluminum as com-

15 pared to cast iron and its liability to batter and widen the ring grooves when the piston is in service. All of these features are present in the piston described.

It is further apparent that the head of the

20 cylinder is in effect two ply or laminated. That is, there is a closed upper end of cast iron or its alloy over which is placed and permanently secured a thickness or ply of aluminum. The aluminum is of much higher heat

25 conductivity. Approximately it conducts heat four times faster than does the lower lamination of iron. Therefore, the heat developed by the explosion will be carried by the aluminum into the cylinder walls and into 30 the water circulation of the engine, while at the inside of the piston, due to the lower conductivity of the iron, it will be relatively cool and there will be no detrimental heating of the oil in the crank case or any carbonizing

35 of the same at the under side of the piston head. Accordingly, I have produced a piston which, has all of the advantages of cast iron so far as the wrist pin bearings are concerned, and so far as resistance at the ring

40 grooves to battering from the rings is concerned, while at the same time the aluminum head in addition to lightening the weight of the piston serves as a rapid conductor of heat to the water circulation of the engine and keeps

45 the piston below said head much cooler than if it was wholly of cast iron.

The invention is described in the appended claims and is to be considered comprehensive of all forms of structure coming within the 50 scope of said claims.

I claim:

1. A composite piston comprising, a piston shell of cast iron, including a skirt, wrist pin bosses integral therewith and an integral top, 55 said top and the upper portion of the sides of said shell having spaced ribs projecting upwardly from the top and outwardly from said sides, and a head of aluminum cast over the top and the upper portions of the sides of said shell, the upper side of the top of said head lying flush with the upper sides of the ribs on the top of said shell and the outer depending sides of the aluminum lying flush with the ribs at the sides of said shell.

60 2. A construction containing the elements

in combination defined in claim 1, said ribs being undercut at their sides and ends so that the ribs are wider at their outer portions than where they join the shell, the aluminum filling the recesses made by said undercuts, 70 whereby a permanent and secure interengagement and interlocking of the aluminum and cast iron is made.

3. A piston comprising, a shell of cast iron including a skirt, wrist pin bosses and top integral with each other, the upper end of said shell having a plurality of spaced apart ribs extending outwardly from the shell there being grooves between said ribs and said ribs at their lower ends terminating short of the 80 skirt of said piston, whereby grooves are made between the lower ends of the ribs and the upper end of the skirt, an aluminum top for the piston over the upper end of said shell filling said grooves and extending over 85 the top of the shell, and ring grooves around the upper end of the piston through said ribs and the sides of the aluminum head.

4. A piston construction comprising, a shell of cast metal including a skirt, wrist pin 90 bosses and a closed upper portion of less diameter than the skirt formed as an integral casting, said upper end portion of the shell having radial ribs projecting upwardly from the top joining at their outer ends with depending spaced apart ribs integral with the shell extending so as to lie in the same plane with the outer sides of the skirt, and an aluminum head cast over the upper end portion of the shell having its upper side flush 100 with the upper ribs and depending sides flush with the outer sides of the side ribs of said shell, and piston ring grooves around the upper end portion of said piston through the side ribs of the shell and through the depending aluminum portions of the shell between 105 said ribs.

5. A construction containing the elements in combination defined in claim 4, said ribs having undercut sides and ends whereby the 110 outer sides of the ribs are wider than where they join the shell and said vertical side ribs terminating at their ends short of the upper end of the skirt, the aluminum filling the spaces between the lower ends of the vertical side ribs and the upper end of said skirt and entering the undercut recesses of said ribs to make a firm and secure interlock between the aluminum head and cast iron shell of the piston.

6. A piston comprising, a cylindrical metallic shell having a portion of its periphery of reduced diameter, spaced apart longitudinal ribs extending outwardly from the reduced portion of the shell and a metal of higher heat conductivity than the shell located between said ribs in said reduced portion, the outer surface of said ribs and said metal between the ribs being shaped to conform to the outer surface of the shell.

7. A piston comprising, a cylindrical metallic shell having a portion of its periphery of reduced diameter, spaced apart longitudinal ribs extending outwardly from the reduced portion of the shell and a metal of higher heat conductivity than the shell located between said ribs in said reduced portion, the outer surface of said ribs and said metal between the ribs being shaped to conform to the outer surface of the shell, and ring grooves 10 in that portion of the cylinder composed of said ribs and said metal between the ribs.

In testimony whereof I affix my signature.

DONALD J. CAMPBELL.
